TYPE-WRITING MACHINE.

1,099,982.

Specification of Letters Patent. Patented June 16, 1914.

Application filed October 3, 1907. Serial No. 395,718.

To all whom it may concern:

Be it known that I, CHARLES H. HUNTER, a citizen of the United States, and a resident of Chicago, county of Cook, and State 5 of Illinois, have invented certain new and useful Improvements in Type-Writing Machines, of which the following is a specification.

The invention relates to improvements in typewriting machines and more particularly to visible typewriting machines, and seeks to provide a simple and effective key-lever and type-bar mechanism which will obviate the necessity of employing intermediate sub-levers or bell-cranks, such as heretofore 15 usually employed in visible typewriting machines.

A further object of the invention is to provide an improved arrangement of type-bar hangers which afford wide bearings for the type-bars and with which a series of uniform type-bars may be employed.

The invention consists in the features of construction, combinations and arrangements of parts hereinafter set forth, illustrated in the accompanying drawings and more particularly pointed out in the appended claims.

In the drawings, Figure 1 is a view in longitudinal section through the improved machine, with certain of the parts omitted for the sake of clearness. Fig. 2 is a detail plan view showing some of the type-bar hangers, the type-bars being shown in section. Fig. 3 is a view in elevation of some of the type-bar hangers and type-bars. Fig. 4 is a detail view of the pivoted end of one of the type-bars. Fig. 5 is a detail section on line 5-5 of Fig. 4. Figs. 6 and 7 are views in elevation of the two forms of type-bar hangers employed. Fig. 8 is a plan view of one of the type-bar hangers. Fig. 9 is a diagrammatic plan view showing a full set of type bars and key levers, the 45 points of connection of the actuating links with the type bars and with the key levers being indicated. Fig. 10 is a fragmentary sectional view taken on a plane indicated by the line x-x of Fig. 1. Fig. 11 is a fragmentary sectional view taken on a plane indicated by the dotted line y-y of Fig. 1.

The form of the machine may be of any suitable or desirable construction and, as shown in the drawings, comprises the base 50 portion 10 mounted on suitable feet 11 and

provided with corner posts 12 and side frames 13. The upper front and rear portions 14 and 15 are sustained from the corner posts 12 and side upright frames 13. The carriage 16 for sustaining the cylindrical platen 17 may be of any usual or suitable construction, but as shown, the base of the carriage is preferably arranged in a plane inclined to an angle of about 45° to the horizontal and is mounted to shift between upper and lower guide rails 18 and 19. If desired, anti-friction balls or rollers 20 may be interposed between the carriage and the guide rails thereof.

The type-bars are pivoted upon a segment 70 arranged in front of and below the platen 17 so as to strike at a common printing point at the front of and above the center of the platen and substantially mid-way between the front and top of the platen so 75 that the printing point is in the direct line of vision of the operator. With the printing point so located, the writing is more easily read than if the printing point is at the front or on the top of the platen. The 80 segment 21 is preferably of the flat or disk type and is upwardly and rearwardly inclined, as shown, so as to be parallel to a tangent plane through the printing point and somewhat below this plane, as shown. 85 The tangent plane through the printing point on the platen is indicated in Fig. 1 by the dotted line a-a. The segment is provided with a center lug 22 secured by a screw 23 to a cross bar 24 at the lower front 90 portion of the machine and the segment is also provided with side lugs 25 secured by screws 26 to the side frames 13. The type-bars 27 are pivotally mounted in suitable 95 hangers 28 upon the upper face of the type-bar segment and the type-bars, in idle position, extend upwardly and forwardly from their pivot points at an angle of about 45° to the horizontal to a suitable type-bar rest 29 sustained by the front upper portion 100 14 of the machine frame. From idle position, the type-bars swing rearwardly to striking position (shown by dotted lines in Fig. 1) and in which position the type-bars 105 are upwardly and rearwardly inclined, as shown, so that the printing point is substantially mid-way between the front and top of the platen.

The key-levers 30 are provided as usual at their forward free ends with the rows or 110

banks of finger keys 31 arranged at the lower front portion of the machine frame. From the front of the machine the key-levers extend rearwardly beneath the type-bars and their rear fulcrumed ends are elevated or extend upwardly to a fulcrum 32 at the upper rear portion of the machine frame. Preferably, the forward portions of the key-levers are substantially horizontal while the rear portions thereof are inclined upwardly and rearwardly and are substantially parallel to the type-bar segment 21. The key-levers are all held in normal elevated position with their forward portions against the transverse stop-bar 33, by springs 34 which are connected at one end to the key-levers adjacent the pivot or fulcrum 32 and at their other ends to a transverse cross bar 35. By thus elevating the fulcrum ends of the key-levers to the upper rear portion of the machine frame and arranging the type-bars upon an upwardly and rearwardly inclined segment in front of and below the platen, the type-bars and key-levers may be directly connected by a series of pull-links 36.

In the ordinary form of front strike typewriting machines, the type-bars are horizontal in idle position or substantially so, and are swung from this horizontal position to a vertical striking position. With a type-bar of this sort it is necessary to exert a horizontal pull or push to properly shift the type-bar without strain on its bearings to the printing point. The usual form of key-lever however, moves in a vertical direction so that it is necessary to interpose some form of intermediate sub-lever or bell-crank to transmit the movement of the key-lever to the type-bar. By arranging the type-bars in front of the platen so as to swing from an inclined idle position on one side of the vertical plane to an oppositely inclined striking position on the other side of the vertical plane, the pull is properly exerted thereon by inclined links extending substantially in line with the idle positions of the type-bars and substantially at right angles to the striking positions thereof. The key-levers are caused to move in inclined direction or in line with the connecting links 36 by elevating the rear fulcrum ends, as described, so that the links 36 may be connected directly to the upwardly inclined rear portions of the key-levers without interfering with the proper transmission of motion from the key-levers to the type-bars. That the motion is properly transmitted through the direct connecting links 36 is shown by the fact that these links are tangent to the arcs on which their points of connection with the key-levers move or, in other words the links are substantially at right angles to a plane extending through the fulcrums of the key-levers and the points of connection

between the key-levers and links. The pivoted ends of the type-bars are elbow-shape and the pull-links 36 are connected to the corners of the elbow-shaped portions so that the links are normally tangent to the arcs on which their points of connection with the type-bars move. The rear portions of the bent key-levers, as stated, are preferably substantially parallel to the type-bar segment, *i. e.*, are inclined upwardly and rearwardly at an angle of substantially 45° to the horizontal. The type-bars when in idle position and the connecting links are oppositely inclined and are substantially at right angles to the type-bar segment and rear portions of the key-levers. This arrangement, as stated, permits of direct one-piece connections between the key-levers and type-bars so that the key action of the machine is extremely light and easily operated. Moreover, there is necessarily less lost motion in the key action than where intermediate sub-levers or bell-cranks are employed and the mechanism is less expensive and more durable. It should also be noted that the pull upon the connecting links is in the direct line with the movement of the key-levers and corresponding type-bars so that there is no side strain upon the bearings and joints. The key-levers are considerably longer than the key-levers ordinarily employed without increasing the size of the machine, and the links are connected to the key-levers at considerable distances from their fulcrums so that the necessary dip or extent of depression of the several keys is slight and uniform and the machine will have an easy, light touch.

In a typewriting machine in which the type-bars are pivotally mounted upon a ring or segment to strike in a common printing point and in which the type-bars are operated by levers connected directly to the type-bars by links, it is necessary, in order to get the proper, straight pull upon all of the type-bars, that the fulcrum of the lever so directly connected to a type-bar and the point of connection of the lever with its link shall be in a line that is substantially parallel to the type-bar ring or segment and that the connecting link shall lie and shall move in a direction substantially at right angles to such a line and substantially at right angles to the plane of the segment. In an understrike typewriter, the parts are so disposed that these conditions may be fulfilled and at the same time directly connect the type-bars with the key-levers. In a front strike typewriter, however, to get this proper action, it has been found necessary to employ upwardly-projecting sub-levers to which the links may be connected, so that a straight pull or push can be transmitted through the links to the type-bars. With the arrangement set forth, however, the

necessity of employing intermediate sub-levers is obviated and the type-bars are directly connected to the key-levers. At the same time the conditions are such that there is a straight effective pull upon all of the type-bars, both at the center and at the ends of the segment, since the fulcrum of the key-levers and the points of connection between the key-levers and the type-bars lie substantially in a common plane parallel to the type-bar segment, and since the pull links are arranged and move in a direction that is substantially at right angles to this plane and to the plane of the type-bar segment. Moreover, as stated, the pull links are arranged and move in a direction that is substantially in line with the normal positions of the several type-bars and at right angles to the striking position thereof. It is necessary that these conditions be preserved in order that the machine shall have a light and easy key action which shall be substantially uniform at all portions of the keyboard. It should be noted that with the construction set forth in which the key-levers are elevated at their rear ends and fulcrumed at the upper, rear portion of the machine, that the pull upon the links and type-bars is backward, as well as downward, as is necessary in order to properly operate the type-bars both at the center and at the ends of the type-bar segment.

The arrangement of all of the type bars, key levers and connecting links comprised in the full type bar system will be clearly understood from a consideration of Figs. 1, 9, 10 and 11. As appears from Fig. 9 the links 36 at their points of connection with their type bars will lie in arcs indicated as *b*, *c*, *d* and *e* corresponding with the four tiers of hangers, each arc containing the links that operate on the type bars included in one tier only. It will be understood that while in horizontal plan view these arcs appear separated as shown, they will coincide with one another when viewed from a plane perpendicular to the type bar segment and also to the rear inclined portions of the key levers. In said Fig. 9 the points of connection of the links with the key levers will lie in a curve indicated by the dotted line *f*. The connections of the left-hand half of the set of links 36 with their respective key levers are more fully shown in Fig. 10 where- 55 in the links of the three type bars fragmentarily shown in Fig. 11 are designated as 36^a, 36^b and 36^c. These selected three type bars all lie in the uppermost tier. The type bar 27 operated by the link 36^a is at the middle of the tier. The type bar operated by the link 36^c is the left-hand end type bar of the tier and the type bar operated by the link 36^b is between the middle and end type bars. It will be apparent that not 60 only these three type bars, selected as typically

illustrative of conditions at different points, but also every other type bar of the set or system, receives a straight, direct pull from its associate link, there being no flaring or fanning of the links due to a difference in the width of the type bar system and key lever system. These two systems in the present construction are substantially equal in width and the links near or at the ends of the system pull as straight as do the middle links. 70 The actuating links are all practically parallel and all exert a practically straight pull as nearly as these results can be arrived at by manufacturing processes. Where in the claims there are recitals to the effect that the links are arranged and move in a direction at right angles to the plane of the type bar segment, and to the plane of the rear portions of the key levers, and in line with the type bars, and like recitals bringing out the 80 construction which enables a practically straight pull of all of the links on their type bars to be obtained, it is to be understood that this construction is to be followed as nearly as it can be in practical manufacture, and that it means a straight pull on all of the type bars by parallel links as contrasted with a set of links in which there is an intentional, systematic and necessary divergence from parallelism and from a 90 straight pull and also in which there is a progressive variation of the links in this respect as they approach the sides of the 95 system.

By elevating the rear portions of the key-levers the universal bar and dog-rocker may be formed in one piece or mounted to swing upon the same bearings. As indicated in the drawings, the universal bar 37 extends transversely beneath the rear ends of the 105 key-levers and is fixed at its ends to rock arms 38 extending from a cross shaft 39 journaled between the rear posts 12 of the machine. A dog-holder 40 is fixed to or formed in one piece with the universal bar 110 and is provided with a pair of escapement dogs 41 of any usual or suitable construction which coöperate with a suitable escapement wheel 42. The escapement wheel 42 is fixed to the lower end of an inclined 115 shaft 43 which is journaled at its upper end in a bracket 44 projecting rearwardly from the lower carriage guide rail 19. At its lower end, shaft 43 is journaled in the bracket 45 that is fixed to and projects inwardly from the rear portion of the base of the machine. At its upper end the escapement shaft 43 is provided with a pinion 46 which meshes with a rack 47 that is secured to the carriage. The shaft 39 is provided with a projecting arm 48 which shifts between a pair of stop screws 49 that are adjustably threaded through lugs 50 on the corner post 12. A spring 51 extending between the arm 48 and a pin 52 on the ma- 120 125 130

chine frame holds the arm 48 normally in engagement with the lower stop screw 49 and holds one of the dogs normally in engagement with the escapement wheel 42.

5 The improved arrangement thus permits the mounting of one of the members of the escapement directly upon the universal bar. It will be understood that any suitable form of escapement may be employed.

10 The type-bar segment 21 is preferably flat, as stated, and is provided with a broad upper surface upon which the type-bar hangers 28 may be firmly secured. The type-bar hangers are formed of sheet metal 15 bent to a U-shape, as shown, and are preferably arranged side by side in a regular series upon the outer, upper face of the type-bar segment. The segment is provided with two series of transverse threaded openings 20 53 and each of the U-shaped hangers is rigidly secured in place by a pair of headed screws 54 extending between the sides of the hangers and engaging the threaded openings 53 of the type-bar segment. The 25 hangers are preferably all of uniform height and each is provided at its inner portion with a pair of divergent pivot-supporting arms 55 which are of considerable less height than the hangers themselves and

30 are arranged at different distances from the lower edges of the hangers so that, when the hangers are mounted in position, the arms 54 are arranged in different planes parallel to the segment. The hangers and

35 type-bars are arranged in sets of three or more and, in the form shown, there are four hangers and type-bars in each set so that the pivot-supporting arms 55 of each hanger may be widely separated and are 40 staggered or overlapped with reference to the corresponding arms on the adjacent hangers to provide wide pivot bearings for the type-bars. The arms 55 of the type-bar hangers are provided with openings 56

45 (see Figs. 6, 7 and 8) at their outer divergent ends to receive the type-bar pivots 57. Adjacent the inner ends of the arms 55 are provided with openings 58, one of which is threaded to receive an adjusting stud or 50 bolt 59. This adjusting stud extends loosely through one of the openings 58 and is threaded into the other so that the arms of the hangers may be brought together to take up the wear upon the bearings. Each of 55 the adjusting studs is provided with a lock-nut 60.

The hangers, as stated, are arranged in sets of four and the arms 55 of the several hangers in each set are arranged in regular 60 order one above the other and are staggered or overlapped, as clearly shown in Figs. 2 and 3. Only two kinds of hangers however are necessary. The first hanger of the set is shown in Fig. 6 and a similar hanger, 65 when inverted, will form the fourth or last

hanger of the set. The projections 61 however, on the hanger are preferably cut off on the dotted line indicated in Fig. 6 on the last or fourth hanger of the set, so as to permit ready access to the adjusting stud 70 and lock-nut on the first hanger of the next adjacent set. The second and third hangers of each set are illustrated in elevation in Fig. 7. The second hanger is set in position there shown while the third hanger is set 75 in inverted position and the projections 62 thereon are cut off on the dotted line indicated. The hangers are of simple form and are strong and durable. They are mounted upon the outer face of the type-bar segment where they are readily accessible and may be easily removed for repairs or the like, and may be easily adjusted. By providing two screws for holding each of the hangers, the type-bars are securely held in 80 permanent alinement. Moreover, the alinement of the type-bars may be easily and quickly effected by entirely loosening one of the screws and partially loosening the other.

In machines provided with overlapping or staggered hangers it is usual to employ type-bars of different forms which renders the machine expensive and interferes with the uniformity of the type-bar action. It 90 will be noted that two of the type-bar bearings 56 of each set of four are arranged below the plane tangent to the platen through the printing point thereof and the other two bearings arranged above the plane, and that all of the bearings are practically the same radial distance from the printing point so that the type-bars may all be of the same lengths. Moreover, by arranging the hangers in sets of three or 100 more with their pivot-sustaining arms staggered or overlapped, long type-bar pivots may be employed which are uniform in length throughout all portions of the type-bar segment and the type-bars themselves 110 may be entirely uniform in construction so that the construction is inexpensive and affords a key action which is uniform throughout.

The type-bars are preferably short, heavy 115 and strong and are formed of drop forgings. Their pivoted ends are elbow shaped as stated, the pivots 57 being carried at the end of the elbow and the openings 63 for the pull links 36 at the corners thereof. Just above the pivoted ends the type-bars are substantially Z-shaped in section, as shown in Fig. 5, so that recesses 64 and 65 and strengthening ribs 66 and 67 are formed on opposite sides of the type-bars. The cut-away portion or recess 64 on one side of the type-bar is opposite the strengthening rib 67 on the other side and the cutaway portion or recess 65 on the inner side of the type-bar is opposite the strengthening rib 66 on the 120 125 130

outer side thereof so that the inner ends of the type-bars are sufficiently strong and heavy in spite of the recesses 64 and 65. These recesses permit the close compact arrangement of the type-bars with the pivots thereof and bearing arms 55 of the hangers, all at the same distance from the printing point. That is to say, when the type-bars are arranged in the manner set forth the recesses 64 on the outer faces of the second, third and fourth type-bars of each set will receive the adjacent arms 55 of the first, second and third hangers when the type-bars are in idle position and the recesses 65 on the inner faces of the first, second and third type-bars of the set will receive the arms 55 of the second, third and fourth hangers when the type-bars are in striking position.

It should be noted that all of the type-bars are entirely similar and uniform in construction so that they are inexpensive to manufacture. This is permitted in spite of the fact that the pivot bearing portions are overlapped to provide long bearings by arranging the hangers and type-bars in sets of three or more. Moreover, by arranging the pivot bearing arms of the hangers of each set in different planes but all at substantially the same radial distance from the printing point, type-bars of uniform length may be employed but, when in idle position the ends of the type-bars and the type thereon are not arranged side by side but are staggered and widely separated so that all danger of collision between the type is avoided.

The present invention provides a bar action for visible typewriting machines which is strong, simple and durable in construction in which the number of parts is materially reduced and in which the printing point is in direct line of vision of the operator.

It is obvious that numerous changes may be made in the details set forth without departure from the essentials of the invention as set forth in the claims.

Having described my invention, what I claim as new and desire to secure by Letters Patent, is:—

1. In a typewriting machine, the combination with the machine frame and platen mounted thereon, of a series of key-levers having keys at their forward, lower ends and having elevated rear ends fulcrumed at the upper rear portion of the machine frame, a type-bar segment arranged below the platen, a series of type-bars pivoted on said segment to strike at a common printing point at the front of the platen, and a series of pull links directly connecting said type-bars and key-levers, the fulcrum of each key-lever and the point of connection between it and its link being in a line parallel

to said segment and each link being arranged and moving in a direction at right angles to said line and to the plane of the type-bar segment, substantially as described.

2. In a typewriting machine, the combination with the machine frame and the platen mounted thereon, of a series of key-levers pivoted at the upper rear portion of the frame and having a series of finger keys at the lower front portion thereof, a series of type-bars pivoted on a curved line and having a common printing point between the front and top of said platen, an inclined segment whereon said type-bars are mounted and a series of links directly connecting said type-bars and said key-levers, said links being arranged and moving in directions at right angles to the plane of said segment, substantially as described.

3. In a typewriting machine, the combination with the machine frame and the platen carried thereby, a series of type-bars pivoted on a curved line and having a common printing point at the front of the platen, said type-bars being normally inclined to the horizontal and a series of key-levers having upwardly inclined rear portions that are substantially at right angles to the normal position of the type-bars and a series of inclined links directly connecting said type-bars and key-levers and arranged at right angles to the rear portions of said key-levers, substantially as described.

4. In a typewriting machine, the combination with the machine frame and the platen mounted thereon, of an inclined type-bar segment in front of and below the platen, a series of type-bars pivoted on said segment and having a common printing point at the front and above the center of the platen, said type-bars in normal position being at right angles to said segment, a series of key-levers having keys at their forward free ends extending beneath said type-bars and having elevated rear fulcrumed ends, pull links directly connecting said type-bars and key-levers, the fulcrums of said key-levers and the points of connections between said key-levers and links lying in a plane substantially parallel to the plane of said segment and said pull links being inclined and arranged in line with said type-bars and at right angles to said plane, substantially as described.

5. In a typewriting machine, the combination with the machine frame and platen mounted thereon, of a type-bar pivoted in front of and below the platen, said type-bar being upwardly and forwardly inclined in idle position and rearwardly inclined in striking position, a key-lever having an upwardly extended rear end pivoted to the upper, rear portion of the machine frame and having a finger-key at the lower, front portion of the machine frame and a link di-

- rectly connecting said type-bar and said key-lever, the pivot of said key-lever and the point of connection between said lever and said link being in a line substantially parallel to the striking position of said type-bar and substantially at right angles to the idle position thereof, and said link extending and moving in a direction at right angles to said line, substantially as described.
6. In a typewriting machine, the combination with the machine frame and platen mounted thereon, of a series of type-bars having a common printing point at the front of the platen, a segment parallel to a tangent through the printing point whereon said type-bars are mounted, a series of key-levers having keys at the lower, forward portion of the machine frame and having elevated rear portions fulcrumed at the upper, rear portion of the frame, links directly connecting said type-bars and said key-levers, the fulcrums of said key-levers and the points of connection between said key-levers and links lying substantially in a common plane parallel to said segment and said links being arranged and moving in directions at right angles to said plane and to the plane of said segment.
7. In a typewriting machine, the combination with the machine frame and the platen mounted thereon, of an upwardly and rearwardly inclined segment arranged in front of and below said platen, a series of type-bars pivoted on said segment and having a common printing point at the front and above the center of said platen, said type-bars being upwardly and forwardly inclined in idle position and upwardly and rearwardly inclined in striking position, and a series of key-levers having keys at the lower front portion of the machine frame and extending rearwardly beneath said type-bars, the rear fulcrumed ends of said key-levers being elevated above the forward ends thereof and a series of pull links directly connecting said type-bars and key-levers, a plane through the points of connection of said links with said key-levers and through the fulcrums of said key-levers being substantially parallel to said inclined segment and said links extending at right angles to said plane, substantially as described.
8. In a typewriting machine, the combination with the machine frame and the platen mounted thereon, of an upwardly and rearwardly inclined segment arranged in front of and below said platen, a series of type-bars pivoted on said segment and having a common printing point at the front and above the center of said platen, a series of key-levers having keys at the front, lower portion of the machine frame and having upwardly and rearwardly inclined rear portions extending to an elevated fulcrum at the upper, rear portion of the machine frame, the rear portions of said key-levers being substantially parallel to said inclined segment and pull links directly connecting said type-bars and said key-levers, said pull links being arranged in line with the normal idle position of said type-bars and at right angles to the rear inclined portions of said key-levers, substantially as described.
9. In a typewriting machine, the combination with the machine frame and the platen mounted thereon, of a series of type-bars having a common printing point at the front and above the center of the platen, an inclined segment parallel to a tangent through the printing point whereon said type-bars are mounted, a series of key-levers having keys at the forward lower portion of the machine frame and having elevated rear portions extending to a common fulcrum at the upper rear portion of the main frame and a series of pull links directly connecting said type-bars and key-levers, said pull links being arranged at right angles to the plane of said inclined segment and to a plane extending through the fulcrums of said key-levers and the points of connection between said key-levers and links, substantially as described.
10. In a typewriting machine, the combination with the machine frame and the platen mounted thereon, of a series of type-bars having a common printing point at the front and above the center of the platen, an inclined segment parallel to a tangent through the printing point whereon said type-bars are mounted, a series of key-levers having keys at the forward lower portion of the machine frame and having elevated rear portions extending to a common fulcrum at the upper rear portion of the main frame, the upper rear portion of said key-levers being substantially parallel to said inclined segment and a series of links directly connecting said type-bars and said key-levers, said links being at right angles to said segment and the rear portions of said key-levers, substantially as described.
11. In a typewriting machine, the combination with the machine frame and the platen mounted thereon, of a series of type-bars having a common printing point at the front and above the center of the platen, an inclined segment parallel to a tangent through the printing point whereon said type-bars are mounted, a series of key-levers having keys at the forward lower portion of the machine frame and having elevated rear portions extending to a common fulcrum at the upper rear portion of the main frame, said type-bars being upwardly and forwardly inclined in idle position and upwardly and rearwardly inclined in striking position and a series of pull links extending

in line with said type-bars and directly connecting the same to said key-levers, said pull links being arranged at right angles to a plane extending through the fulcrums of 5 said key-levers and the points of connection of said key-levers with said links, substantially as described.

12. In a typewriting machine, the combination with the machine frame and the 10 platen mounted thereon, of a series of type-bars having a common printing point at the front and above the center of the platen, an inclined segment parallel to a tangent through the printing point whereon said 15 type-bars are mounted, a series of key-levers having keys at the forward lower portion of the machine frame and having elevated rear portions extending to a common fulcrum at the upper rear portion of the 20 main frame, the rear portions of said key-levers being arranged substantially parallel to said inclined segment and said type-bars being upwardly and forwardly inclined in idle position at right angles to the plane of 25 said segment and a series of pull links extending in line with the idle position of said type-bars and directly connecting the same with said key-levers, substantially as described.

13. In a typewriting machine the combination with the machine frame and the platen mounted thereon, of a series of type-bars having a common printing point at the 30 front and above the center of the platen, an inclined segment parallel to a tangent through the printing point whereon said type-bars are mounted, a series of key-levers having keys at the forward, lower portion of the machine frame and having elevated 35 rear portions fulcrumed at the upper, rear portion of the frame, said type-bars being upwardly and forwardly inclined in idle position at right angles to the plane of said segment, and a series of pull-links extending 40 in line with the idle position of said type-bars and directly connecting the same with said key-levers, the fulcrums of said key-levers and the points of connection thereof with said links lying in a plane sub- 45 substantially parallel with said segment and at right angles to said pull-links, substantially as described.

14. In a typewriting machine, the combination with the machine frame and the 50 platen mounted thereon, of a series of type-bars having a common printing point at the front and above the center of the platen, an upwardly and rearwardly-inclined segment parallel to a tangent through the printing 55 point whereon said type-bars are mounted, a series of key-levers having keys at the forward, lower portion of the machine and having elevated rear portions fulcrumed at the upper, rear portion of the frame, the

60 rear portions of said key-levers being arranged substantially parallel to said inclined segment and said type-bars being upwardly and forwardly inclined in idle position at right angles to the plane of said segment, and a series of pull-links extending in line 65 with the idle position of said type-bars and directly connecting the same with the upwardly-inclined rear portions of said key-levers, substantially as described.

15. In a typewriting machine, the combination with the platen, of a type-bar segment, a series of separate, independently adjustable hangers mounted on one of the plane faces of said segment having overlapping pivot-sustaining arms and a series of 70 uniform type-bars, one pivoted between the arms of each of said hangers, the pivots of said type-bars being arranged in different planes parallel to and exterior of said segment but at a substantially uniform distance 75 from the printing point of the platen, substantially as described.

16. In a typewriting machine, the combination with the platen, of a type-bar segment, a series of type-bar hangers, each 80 having a pair of divergent pivot-sustaining arms, the arms of adjacent hangers being overlapped and a series of type-bars pivoted between the arms of said hangers, each of 85 said type-bars having a recess on one side to receive the arm of the adjacent hanger and a strengthening rib on its opposite side, substantially as described.

17. In a typewriting machine, the combination with the platen, of a type-bar segment, a set of three or more hangers arranged adjacent each other on one side of 90 said segment and each having a pair of divergent pivot-sustaining arms, the arms of said hangers being overlapped and arranged 95 in different planes parallel to said segment and a set of type-bars pivoted between the arms of said hangers, each of said type-bars having recesses in its opposite sides to receive the arms of the adjacent hangers as 100 it is shifted to and from striking position, substantially as described.

18. In a typewriting machine, the combination with the platen, of a type-bar segment, a set of three or more hangers arranged adjacent each other on one side of 105 said segment and each having a pair of divergent pivot-sustaining arms, the arms of said hangers being overlapped and arranged 110 in different planes parallel to said segment and a set of type-bars pivoted between the arms of said hangers, each of said type-bars being provided adjacent its pivot with a recess and strengthening ribs on its opposite sides to properly overlap the arms of the 115 adjacent hangers, the strengthening rib on one side being opposite the recess on the other side, substantially as described.

19. In a typewriting machine, the combination with the platen, of a type-bar segment, a set of three or more hangers arranged adjacent each other on one side of said segment and each having a pair of divergent pivot-sustaining arms, the arms of said hangers being overlapped and arranged in different planes parallel to said segment and a set of type-bars pivoted between the 5 arms of said hangers, each of said type-bars being substantially Z-shaped in section adjacent its pivot to provide recesses and strengthening ribs to properly overlap the arms of the adjacent hangers, substantially as described.
20. In a typewriting machine, the combination with the platen, of a series of type-bars having a common printing point at the platen, a type-bar segment and a series of 10 type-bar hangers arranged in sets of three or more on one side of said type-bar segment, the hangers of each set having overlapping pivot-sustaining arms arranged in different planes parallel to the type-bar 15 segment, said type-bars being uniform and each being substantially Z-shaped in section adjacent its pivot to form recesses and strengthening ribs to properly overlap the arms of adjacent hangers, substantially as 20 described.
21. In a typewriting machine, the combination with a type-bar segment, of a series of U-shaped hangers arranged side by side on one side of said type-bar segment and 25 separately secured thereto, said hangers being arranged in sets of three or more, the hangers of each set having divergent pivot-sustaining arms overlapped and arranged in different planes parallel to the type-bar segment and a series of uniform type-bars pivoted between the arms of said segment, the 30 pivots of said type-bars being all at the same distance from the printing point of said platen, substantially as described.
22. In a typewriting machine, the combination with a platen, of a flat type-bar segment, a series of type-bar hangers arranged side by side upon one side of said flat type-bar segment, said hangers being 35 separately secured to said segment and arranged in sets of three or more, the hangers of each set having divergent pivot-sustaining arms overlapping and arranged in different planes parallel to the type-bar segment and a series of type-bars pivoted between the arms of said hangers, substantially as described.
23. In a typewriting machine, the combination with a platen, of a series of type-bars, a flat type bar segment and a series of 40 separate, independently adjustable hangers, one for each of said type-bars, arranged side by side and mounted upon the same flat face of said segment, said hangers being ar- 45 ranged in sets of three or more and having 65 projecting, divergent, overlapping, pivot sustaining arms, the pivot points of the hanger arms of each set being arranged in different planes parallel to said segment, said type bars having pivots engaging said 70 arms, substantially as described.
24. In a typewriting machine, the combination with a platen, of a flat type bar segment, a series of U-shaped type bar hangers arranged side by side upon the same 75 flat face of said segment, a pair of screws for separately securing each of said type bar hangers in position, said hangers being arranged in sets of three or more and having divergent, overlapping, pivot sustaining 80 arms, the arms of the hangers of each set being arranged in different planes parallel to the type bar segment, and a series of type bars pivoted between the arms of said hangers, substantially as described.
25. In a typewriting machine, the combination with the machine frame and platen sustained thereby, of a series of type-bars pivoted on a curved line and having a common printing point at the front, upper portion 85 of said platen, a series of key-levers having keys at the lower front portion of the machine frame and having upwardly inclined rear ends extending to a common fulcrum at the upper, rear portion of the machine frame, a universal bar extending beneath the rear inclined portions of said key-levers and an escapement member mounted directly upon said universal bar, substantially as described.
26. In a typewriting machine, the combination with the machine frame and a platen mounted thereon, of an upwardly and rearwardly inclined segment arranged in front of and below the platen, a series of 90 type-bars pivoted on said segment and having a common printing point at the front and above the center of said platen, a series of key-levers having keys at the lower, forward portion of the machine frame and having elevated rear portions fulcrumed at the upper rear portion of the frame, and links directly connecting said type-bars and key-levers, the fulcrums of said key-levers and the points of connection between said key-levers and links lying substantially in a common plane parallel to a tangent through the printing point, and said links being arranged and moving in directions at right angles to said plane.
27. In a typewriting machine, the combination of a platen, type bars, levers provided with finger keys, connections between said type bars and said levers, a universal bar operated on directly by said levers, and an escapement member mounted directly upon said universal bar.
28. In a visible typewriting machine, the

combination of a platen; type bars coöperative therewith; levers provided with finger keys; connections between said levers and said type bars; a universal bar underlying said levers and operative directly thereby; and escapement devices comprising a feed dog and a rack with which said dog co-operates, said dog being mounted directly on said universal bar.

10 29. In a typewriting machine, the combination with a platen, of a system of type bars mounted in an upstanding arc and

striking rearwardly against the platen, a system of bent levers consisting of pendent arms fulcrumed at their upper ends, and 15 forwardly extending key-bearing arms, and forwardly and rearwardly acting links connecting said type bars to the lower ends of said pendent arms; said links extending at right angles to said pendent arms.
